UNITED STATES PATENT OFFICE.

EDWARD H. McMILLAN, OF OAKLAND, CALIFORNIA.

QUICK-ACTION CLAMP.

Application filed December 31, 1925. Serial No. 78,637.

This invention relates to clamps such as are used in applying or fastening a curb iron to a curb form in concrete construction or other concrete work and particularly to 5 a quick action clamp.

An object of the invention is to provide a very simple quick acting clamp which is cheap to manufacture, which may be readily applied and removed, and which will not 10 have any parts thereon which can be seriously affected by the cement after it has hardened, as is the case with the common screw clamp ordinarily used for holding curb irons in place against curb forms.

15 A further object is to provide a device of this kind including a wedge whereby the clamp may be placed in operative engagement with the curb iron and curb form, and provide means whereby this wedge is so connected to the body of the clamp that the wedge cannot be accidentally lost but whereby the wedge may be, if desired, removed.

My invention is illustrated in the accompanying drawings, wherein:—

25 Figure 1 is a transverse sectional view through a curbing mold showing my clamping device applied thereto;

Figure 2 is a side elevation of the outside mold wall and clamping device;

30 Figure 3 is a top plan view of the structure shown in Figure 2;

Figure 4 is a perspective view of the wedge.

Referring to this drawing, it will be seen 35 that I have illustrated the forms for making concrete curbs. These forms consist of the inner form 10 and the outer form 11. Disposed against this outer form 11 on the inside face thereof adjacent the upper edge 40 is a curb iron 12, and an anchor bolt 13 has its head engaged with this protecting iron 12 and extends laterally therefrom and is then downwardly bent so as to extend into the space between the curb forms 10 and 11

45 and which is filled with the concrete 14. The lower edge of the outer curb form 11 is downwardly and outwardly curved, as at 15, so as to form the rounded gutter of the curb and cause the curb to merge into the plane 50 of the roadway. So far I have described a common manner of forming concrete curbings.

55 My invention, as before stated, relates to the clamp whereby this curb iron 12 is held in engagement with the form 11 while the concrete is hardening. My device consists

of a clamp formed of a body which is approximately U-shaped in cross section and comprises the straight transverse bar 16 and the downwardly extending leg 17 on the 60 inside end of this bar. This leg is adapted to bear against the upper outside face 18 of the part 12. The opposite end of the body is formed with the downwardly extending leg 19 which at its lower end is inwardly 65 bent, that is, the extremity 20 is bent toward the opposite leg 17. Thus when this clamp is placed over the top of a form 11, a rectangular space will be formed between the body of the clamp, the leg 19, the inwardly 70 turned portion 20, and the form, and in this rectangular space a wedge 21 is adapted to be driven. This wedge may be of any suitable material as, for instance, hard wood. As this wedge is driven inward it draws the 75 clamp laterally and draws the leg 17 against the iron 12, holding this iron in proper position against the form and with relation to the concrete so that when the form 11 is withdrawn after the concrete has hardened, 80 this curb iron 12 will be disposed in place at the upper outside corner of the curbing 14.

In order to prevent the accidental loss of the wedge 21, I have illustrated the under face of the wedge 21 as formed with a longitudinally extending slot 22 which is less in length than the total length of the wedge, and I have illustrated the inwardly turned extremity 20 as being screw-threaded for the passage of a withdrawable pin in the form 90 of a screw 23 which screws into the screw-threaded opening in the portion 20 and has a rounded extremity which fits within the groove 22. Thus when this screw is turned up it will extend into the groove 22 and will 95 prevent this wedge in any way being removed even when the clamp is detached from the form 11. This prevents the wedge from being lost and renders it a unit with the clamp 16.

100 In the use of this device, after a form has been placed, the iron 12 is disposed at the upper inner corner of the form and held in place by means of a plurality of the clamps formed of the portions 16, 17 and 19. These 105 clamps are then turned upward so that the leg 17 jams the plate or iron 12 against the inside face of the form and holds it firmly in place. The clamp 16, inasmuch as it rests upon the upper face of the form 11, constitutes a stop which aids in positioning the curb iron 12 inasmuch as this curb iron may 110

be forced upward until its upper edge engages with the clamp 16 and then the clamp may be locked by driving in the wedge so that no particular skill need be used in placing the curb irons and properly positioning them with relation to the curb. Of course, when the wedge becomes worn or should become broken or it be desired to remove the wedge for any reason, the screw 23 may be released and the wedge taken out and a new one replaced, but normally this screw holds the wedge from detachment and at the same time allows it free longitudinal movement to a sufficient degree to cause the tightening of the clamp. The leg 19 has its inside face inclined complementarily to the inclined face of the wedge 21. Preferably this wedge has its inclined face disposed at a relatively great degree of inclination so as to secure rapid action when the wedge is forced inward.

It will be seen that this device is inexpensive to make, that it may be quickly adjusted to suit the work, that it is easily and quickly applied or removed, that it is particularly efficient as a holding means, and that it is easily kept clean. Further it will be noted that it is of such construction that it will not mar the finished work and that there is no part which is seriously affected by any hardened cement. Common screw clamps are ordinarily used for this purpose and these are very readily affected by the hardened cement and rendered useless.

This clamp might be used for many other purposes than for holding curb irons or curb molds and this use of the device is only one of many other uses as the clamp is capable of a large number of different applications and the drawing merely illustrates one use of the clamp.

While I have illustrated this clamp as applied to holding a curb iron to a curb mold, I do not wish to be limited to this use of the device as it might be used for other purposes. Neither do I wish to be limited to the exact details of construction as illustrated, as these might be changed and modified in many minor ways without departing from the spirit of the invention as defined in the appended claims.

I claim:

1. A clamp for the purpose described including a body having an inner, downwardly extending leg and an outer downwardly extending leg, a wedge disposed inward of the

outer leg and having an outer inclined face, the outer leg being complementarily inclined to said face, the wedge having a longitudinally extending recess, and a pin carried by the clamp and extending into said recess, the recess being less in length than the wedge whereby to detachably hold the wedge against accidental displacement but permit of the longitudinal movement of the wedge. 65

2. A clamp of the character described including a body having a downwardly extending leg on its inner end and a downwardly extending leg on its outer end, the lower end of this leg being inwardly turned toward the first named leg, a wedge disposed immediately above this inwardly turned end and between it and the body of the clamp, the wedge having a longitudinally extending recess, and a pin carried by the clamp and extending into said recess, the recess being less in length than the wedge. 75

3. A clamp of the character described comprising a straight body adapted to be disposed upon the top of a mold board and having at one end a downwardly extending leg, the opposite end of the body having a downwardly extending leg, the lower extremity of which is inwardly turned toward the first named leg, a screw-threaded pin extending upward through said inwardly turned extremity, and a wedge disposed between the inwardly turned extremity and the body of the clamp and bearing against the adjacent leg, said wedge having a longitudinally extending groove less in length than the wedge and closed at its opposite ends into which said pin extends. 85

4. A clamping device of the character described including a clamping body adapted to extend over and embrace a mold board and a curb iron, a wedge operatively engaging said body and adapted to engage the outer face of the mold board and when driven home urging the curb iron against the mold board, the wedge being formed with a longitudinally extending recess, and the body of the clamp having a pin engaging said recess, the recess being less in length than the length of the wedge, said pin and wedge permitting free longitudinal movement of the wedge but holding the wedge against accidental displacement from the body of the clamp. 100

In testimony whereof I hereunto affix my signature.

EDWARD H. McMILLAN.
